VEHICLE OUTSIDE DOOR HANDLE

William L. Mitchell, Bloomfield Hills, Mich., assignor to General Motors Corporation, Detroit, Mich., a corporation of Delaware

Application May 18, 1949, Serial No. 2,729

Term of patent 7 years

(Cl. D10—8)

To all whom it may concern:

Be it known that I, William L. Mitchell, a citizen of the United States, being a resident of Bloomfield Hills, county of Oakland, State of Michigan, have invented a new, original, and ornamental Design for a Vehicle Outside Door Handle, of which the following is a specification, reference being made to the accompanying drawing, forming a part thereof.

In the drawing:

Figure 1 is a side elevational view of a vehicle outside door handle, showing my new design.

Figure 2 is a plan view thereof.

Figure 3 is an end elevational view thereof.

Figures 4 and 5 are sectional views thereof taken on lines 4—4 and 5—5 of Figure 1 respectively.

I claim:

The ornamental design for a vehicle outside door handle, substantially as shown.

WILLIAM L. MITCHELL.
